UNITED STATES PATENT OFFICE.

JOHN M. HAMOR, OF PHILADELPHIA, PENNSYLVANIA, ASSIGNOR TO JOHN M. ROGERS, OF WILMINGTON, DELAWARE.

ROCK-DRILL.

SPECIFICATION forming part of Letters Patent No. 593,214, dated November 9, 1897.

Application filed March 31, 1897. Serial No. 630,040. (No model.)

To all whom it may concern:

Be it known that I, JOHN M. HAMOR, a citizen of the United States, residing at Philadelphia, county of Philadelphia, and State of Pennsylvania, have invented a new and useful Improvement in Rock-Drills, of which the following is a full, clear, and exact description, reference being had to the accompanying drawings, which form a part of this specification.

My invention has for its object a novel construction of valve and its connection with the piston of the rock-drill, whereby air or other pressure fluid is alternately admitted to opposite ends of the rock-drill piston, which causes it to reciprocate.

My invention consists also in providing the head of the rock-drill with an engine operated by the same air or other fluid which operates the piston, the engine being used for the purpose of rotating the drill, so as to present different cutting edges of the tool to the work.

I will first describe my invention as illustrated in the accompanying drawings, and then particularly point out my invention in the claims.

In the drawings, Figure 1 is a vertical longitudinal section through the piston and valve. Fig. 2 is a section on the line 2 2, Fig. 1. Fig. 3 is a section on the line 3 3, Fig. 1. Fig. 4 is a section on the line 4 4, Fig. 1. Fig. 5 is a section on the line 5 5, Fig. 1. Fig. 6 is a detail perspective of valve and piston.

A represents the supporting-frame of the machine, B the drill-head, and B' the piston-rod.

C is the cylinder. Connected to this cylinder is the nut D, which works on the threaded shaft E, operated by the crank F, so that the piston and the cylinder of the rock-drill may be carried by rotating the handle.

B² is the piston, having the heads b and b'. Between them is the cut-away portion b².

G is the valve-casing, and G' is the live-air chamber of the valve, to which the live air or other fluid is admitted through flexible passage G², and G³ is the exhaust-passage.

From the live-air chamber G', by means of the passages g³ g⁴, air passes to the space H' on opposite sides of the valve-piston H, and

h and h' are passages leading from the space H' on opposite sides of the valve-piston H to the cylinder C.

H² is the valve.

Leading from the chamber G' there are the 55 passages h³ and h⁴, the passages h³ and h⁴ leading to opposite ends of the cylinder.

In one position of the valve H² the passage h³ is in communication with the exhaust-passage g³, while the passage h⁴ is in communication with the live-air chamber G'. Under these conditions, the piston being in the position shown in Fig. 1, the passage h' from one side of the valve-piston H is in communication with the exhaust, while the passage 65 h is closed by the piston-head b, so that air-pressure is on the side of the piston H corresponding to the passage h. Under these conditions the piston B' will be moved toward the left. It will move so until the portion b² 70 closes the connection with the passage h, at which time the passage h' will be closed by the head b' of the piston. Under these conditions the air will be exhausted from the side of the valve-piston corresponding to the 75 passage h and the live air on the side corresponding to the passage h' will become active. This will shift the valve H², so that the passage h⁴ will be connected with the exhaust and the passage h³ with the live-air chamber 80 G'. As a consequence live air will be admitted to the left side of the piston and the right-hand side will be open to the exhaust, under which condition the piston will be moved in the reverse direction until it reaches the position 85 shown in Fig. 1, at which time the passage h will be closed by the head C of the piston and the passage h' open to the exhaust, and under these conditions the valve will reverse, bringing it again into the position 90 shown in Fig. 1.

So much for the operation of the valve and its control of the piston. The advantage of such a construction as this is that the valve is a rotary valve, and, second, is at all times 95 on both sides under the action of pressure, so that it is always ready to become active. Again, it is very simple in construction and certain in its action.

In order to perform the other novel feature 100

of my invention—to wit, of rotating the piston at the desired points—I prefer the following construction:

The piston B' has a portion of its interior 5 cut out so as to form a rectangular orifice, in which rectangular orifice is placed the shaft I, upon the end of which is mounted the ratchet-wheel J, operated upon by the spring-pawl j, j' . These pawls are operated in the following manner: The pawls are mounted in a ring K, mounted loosely in the head I'. Connected with this ring K is the piston k, which piston is operated in the following manner: In the cylinder C are the ports c, c' , connecting with the passages h^3, h^4 , also connecting with the passages c^2, c^3 , leading to opposite sides of the piston k. In the movement of the valve H² the ports c, c' are alternately connected with pressure and exhaust. The port 20 c admits the air to one side of the piston k and the port c' to the other side of the piston k. The movement of the piston k in one direction causes the pawls either j or j' to act upon the ratchet and rotate the shaft I, and 25 with it the piston, while when the air is admitted to the other side of the piston k it causes the ring J, and with it the pawls, to be moved in the opposite direction, preparatory for another action upon the ratchet. 30 In order to avoid the necessity of having a short crown-tooth or, what is the same thing, a large number of teeth, I use the two pawls, which are so set that one or the other of the pawls is always in active position. By this arrangement the piston is automatically turned at each stroke of the piston.

Instead of the pawls being on the ring they may be placed on the shaft I and the ring K internally toothed, so that motion is transmitted by the movable ratchets acting upon the pawls.

Having now fully described my invention, what I claim, and desire to protect by Letters Patent, is—

45 1. In an automatic engine, in combination, a cylinder, a piston having a cut-away portion, a valve-casing having two chambers one directly in connection with the source of pressure supply and exhaust, the other having 50 two passages leading to the cylinder, a valve in one chamber and a valve-piston in the

other, and passages leading from the valve-chamber to the valve-piston chamber on opposite sides of the valve-piston, and passages leading from the valve-chamber to opposite ends of the piston-chamber.

2. In a rock-drill, in combination, a cylinder, a piston in said cylinder, and pressure and exhaust passages for controlling the reciprocation of said piston, a spindle upon which said piston is adapted to reciprocate and with which it is adapted to rotate, a ratchet mounted upon said spindle, a ring provided with a bearing upon which it is adapted to rotate concentric with the piston rotation, 60 and connection between said ring and the spindle whereby when the ring is moved in one direction the spindle is rotated, a secondary piston connected with said ring, a piston-chamber for said piston and connection between opposite sides of said piston and the main cylinder adjacent to the pressure and exhaust passages.

3. In a rock-drill, in combination, a cylinder, a piston in said cylinder and pressure 75 and exhaust passages for controlling the reciprocation of said piston, a spindle upon which said piston is adapted to reciprocate and with which it is adapted to rotate, a ratchet mounted upon said spindle, a ring provided with a bearing upon which it is adapted to rotate concentric with the piston rotation, a pawl connected with said ring adapted to coact with said ratchet, a secondary piston connected with said ring, a piston-chamber 80 for said piston and connection between opposite sides of said piston and the main cylinder adjacent to the pressure and exhaust passages whereby when in the operation of the main piston pressure is admitted to one side 85 of the secondary piston the pawl is moved into operative position, and when pressure is admitted to the opposite side of said secondary piston the pawl is operated to turn the ratchet and with it the main piston.

In testimony of which invention I have hereunto set my hand.

JOHN M. HAMOR.
